Primary Examiner — Jennifer Rivard

(74) Attorney, Agent, or Firm — Weiss & Moy, P.C.;
Jeffrey D. Moy(57) **CLAIM**

The ornamental design for a hair iron, as shown and described.

DESCRIPTION

FIG. 1 is a perspective view of a hair iron;

FIG. 2 is a front view of the hair iron;

FIG. 3 is a rear view of the hair iron;

FIG. 4 is a left-side view of the hair iron;

FIG. 5 is a right-side view of the hair iron;

FIG. 6 is a plan view of the hair iron;

FIG. 7 is a bottom view of the hair iron; and,

FIG. 8 is a magnified cross-sectional taken along lines 8-8 in FIG. 2.

The broken lines illustrate a portion of the hair iron and form no part of the claimed design.
